UNITED STATES PATENT OFFICE.

LEWIS H. WATSON, OF CHICAGO, ILLINOIS.

PRESS FOR DAMPENING SHIRTS.

SPECIFICATION forming part of Letters Patent No. 373,868, dated November 29, 1887.

Application filed June 28, 1886. Renewed October 4, 1897. Serial No. 251,401. (No model.)

To all whom it may concern:

Be it known that I, LEWIS H. WATSON, a citizen of the United States, residing at Chicago, in the county of Cook and State of Illinois, have invented certain new and useful Improvements in Presses for Dampening Shirts, of which the following is a specification.

Preparatory to ironing shirts or other like articles it is necessary to dampen the same, and this has been usually accomplished by sprinkling. It is desirable that the fabric should be dampened uniformly throughout the sprinkled portion, and this is especially true with regard to the bosom portion of a shirt. In laundries, where a large number of such articles are to be dampened and ironed, means for quickly and effectively distributing the moisture throughout the sprinkled fabric will be found exceedingly convenient and desirable.

The object of this invention is to provide a simple, reliable, and effective construction of press, wherein any desired number of dampened shirts can be conveniently placed in proper shape and then pressed so as to distribute the moisture uniformly throughout the fabric, after which the pressure can be removed and the apparatus readily manipulated so as to remove the pressure device to one side, and thereby permit free access to be had to the articles.

To the attainment of such end my invention consists in matter hereinafter described, and particularly pointed out in the claim.

In the drawings, Figure 1 represents in perspective a shirt-press constructed in accordance with my invention, with the arm or support which carries the platen or pressure device swung to one side. Fig. 2 represents said press, partly in elevation and partly in section, on a vertical central plane. Fig. 3 is an enlarged detail representing a portion of the latching or locking device.

In said drawings, A indicates the table, which is secured upon an appropriately-constructed stand, B. The swinging arm or support for the pressure device is arranged to swing in a horizontal plane over the table, and is supported at one end by a vertical rod or standard, D, which rises from the stand at one side of the table. At its opposite end the

horizontally-swinging arm is provided with means whereby, when it is in position to bring the pressure device over the table, it can be locked. The locking device consists of a rod, 55 E, attached at one end to the free end of the horizontally-swinging arm and at its opposite end provided with a hook, E'. This rod drops down from the swinging arm, in order that when said arm is in position to bring the 60 pressure device properly over the table the hook end of the rod E can be engaged with the eye of an eyebolt, F, that is secured to the stand or table. By such arrangement the rod E not only constitutes a catch for holding the 65 arm against any tendency to swing as long as the rod is in engagement with the eye, but it also ties the free end of the arm to the stand or table, so that the arm shall rigidly resist and oppose the resistance that is necessarily 70 incident to the act of pressing articles upon the table.

The pressure device herein shown is constructed with a plate or platen, G, swiveled upon the lower end of the vertically-arranged 75 adjusting-screw G', which latter is arranged to work through a screw-threaded bearing, with which the swinging arm C is provided at or about a point intermediate of its ends. The eyebolt passes through the top portion, B', of 80 the stand and is held by appropriate nuts, B'. It will here be observed that in order to connect the hook with the eye the free end of the swinging arm can be slightly depressed for such purpose, and that after such engagement 85 the arm will spring up to substantially its normal position. The swinging arm could be pivoted upon the upper end of the rod or standard D, but more desirably it is fitted to and rigidly held upon said standard—as, 90 for example, it can be clamped between a shoulder on the standard or rod and a tightening, E, in which case the rod is mounted so as to be susceptible of an oscillation about its axis. As herein shown, the stand is provided 95 with two bearings for said rod. One of these bearings, H, is arranged at or near the upper portion of the stand, and at a point just under said bearing the rod is provided with a shoulder, D', which prevents the rod from being drawn upward when the pressure device 100 is tightened down upon the articles that are to

be pressed. The bearing H' is fixed at a point below the bearing H , and is formed with a step or socket, into which the lower end of the oscillatory rod is stepped. By the foregoing arrangement of the swinging arm carrying the pressure device and rigid with the oscillatory rod and the bearings for the latter a substantial and steady swinging support is attained.

Preparatory to placing the sprinkled articles upon the table the swinging support carrying the pressure device can be swung around, so as to leave a clear space above the table and permit the operator to properly place the articles upon the table with no hinderance whatever. After this the swinging support can be swung around so as to bring the pressure device in proper operative position and the swinging support then locked, as hereinbefore explained.

It may also be noted that for the sake of lightness and cheapness the arm C can be made of wood, and a threaded bearing, I , for the adjusting-screw be secured to said arm, as herein shown. The table A can also consist of a wooden board secured upon the stand.

The table and stand have hereinbefore, for convenience of description, been referred to as

separate devices. For the purposes of the claim, however, it will be understood that the term "table" comprises a bed such as indicated at A for the articles that are to be pressed to lie upon and some suitable support for said bed.

What I claim as my invention is—

A shirt-press for laundry-work, consisting of the table A , whereon the dampened shirts are to be laid, the overhanging horizontally-swinging arm carrying a pressure device, such as set forth, the vertically-disposed oscillatory rod D , to which the horizontally-swinging arm is at one end secured, the rod E , depending from the opposite free end of the horizontally-swinging arm and having its lower end provided with a hook, and an eye, F , secured to the table and located to be engaged by the hook when the horizontally-swinging arm is in position over the table, said members being constructed, combined, and organized substantially as shown and described, and for the purpose specified.

LEWIS H. WATSON.
